Primary Examiner — Mary Ann Calabrese
Assistant Examiner — Catherine Ho

(57) CLAIM

I claim the ornamental design for gaming desk, as shown and described.

DESCRIPTION

FIG. 1 is a perspective view of a gaming desk, showing my new design;

FIG. 2 is a front elevation view thereof;

FIG. 3 is a bottom plan view thereof;

FIG. 4 is a top plan view thereof;

FIG. 5 is a rear elevation view thereof;

FIG. 6 is a left side view thereof; and,

FIG. 7 is a right side view thereof.

1 Claim, 7 Drawing Sheets
